UNITED STATES PATENT OFFICE.

THOMAS J. RYAN, OF TULSA, OKLAHOMA.

OIL-DISTILLING APPARATUS.

1,397,984.

Specification of Letters Patent. Patented Nov. 22, 1921.

Application filed July 21, 1921. Serial No. 486,359.

To all whom it may concern:

Be it known that I, THOMAS J. RYAN, a citizen of the United States, residing at Tulsa, in the county of Tulsa and State of Oklahoma, have invented new and useful Improvements in Oil-Distilling Apparatus, of which the following is a specification.

This invention relates to oil distilling apparatus.

10 The most common way of distilling crude petroleum oil, for the production of gasoline, is by what is known as the cracking process. According to this process, the hot petroleum oil coming from the shell stills 15 is recharged into pipe stills, under a pressure of from 80 to 100 pounds and at very high temperatures, sometimes as high as 800°. In these pipe stills the oil is cracked and a certain percentage of gasoline is obtained from this oil. An objection to this 20 process, however, is that the distillate is not finished stock, as, owing to the high temperatures to which it is subjected, it is discolored and must be subjected to further treatment at a considerable expense of time and 25 money for the purpose of obtaining a product of proper color.

The object of my invention is to provide 30 an apparatus by means of which crude oil may be treated practically without pressure, and at a very low temperature, whereby the gasoline vapors may be liberated without heating the oil to cracking temperature, and thereby enabling a product of proper color 35 to be directly obtained without further treatment.

40 A further object of the invention is to provide a distilling apparatus embodying two distilling units, one operating to treat crude oil from a source of supply for the liberation of a certain proportion of its gasoline content, and the other operating to treat the product from the first unit for the liberation 45 of the remainder of the available gasoline content, whereby high quality gasoline of proper color for the market may be easily, quickly and inexpensively produced.

50 The invention consists of the features of construction, combination and arrangement of parts, hereinafter fully described and claimed, reference being had to the accompanying drawings, in which:—

55 Figure 1 is a diagrammatic plan view of an oil distilling apparatus embodying my invention.

Fig. 2 is a side elevation of one of the stills.

Fig. 3 is a rear end elevation thereof.

Fig. 4 is a vertical longitudinal section through the still. 60

Fig. 5 is a vertical transverse section thereof taken on line 5—5 of Fig. 4.

Fig. 6 is a diagrammatic sectional view of portions of one of the distilling units of the apparatus. 65

In carrying my invention into practice I provide a distilling apparatus comprising 70 duplicate primary and secondary distilling units A and B, which are substantially alike in character, differing only in the details hereinafter described. Each of these units 75 comprises a pipe still 1, heated in any suitable manner, and having a heating chamber in which is arranged a pipe coil 2, suitably arranged within said chamber and having the inlet and outlet ends 3 and 4. The inlet end 3 of the coil 2 of the pipe still 1 of unit A is connected with a crude oil supply pipe 5 leading from a suitable storage tank or reservoir (not shown). In this pipe 5 may 80 be arranged a charging pump 6 for forcing the oil under a desired low pressure through the still. The outlet end 4 of the coil 2 of each pipe still is connected with a conducting pipe 7 leading therefrom to an expansion 85 tower or tank 8. In each pipe 7 is placed a suitable type of recording temperature gage bulb 9, whereby the stillmen may readily see at all times the temperature of the heated oil passing from the stills to the 90 expansion tanks. The crude oil passing through the primary still 1 of unit A is heated to a maximum temperature not greater than 300° F., while the oil heated in the secondary still of unit B is heated 95 to a maximum temperature not exceeding 400° F.

Each expansion tower or tank 8 is of suitable dimensions and is designed to receive the heated oil from its still. The pipe 7 through which this heated oil passes enters through the side of the tank 8 near its lower end and terminates in an upwardly extending discharge portion or nozzle 10. This nozzle 10 has its upper end terminating 100 a considerable distance below the center of the tank, and ordinarily extends about four feet above the bottom of the tank, or a distance approximately one-third the height 105 of the tank or somewhat less. It will be ob- 110

served that the interior (i. e., expansion space) of the tank is otherwise void of baffles or other obstructions, such space being free and clear and normally without pressure exceeding normal atmospheric pressure. The heated oil flows through the pipe 7 into the tank 8 without any pressure except the head pressure at the level where it discharges into the tower, which ordinarily is at a fifteen foot elevation, and equals substantially seven and a half pounds pressure on the discharge line from the pump. The heated oil flowing through the outlet 10 passes into the unrestricted comparatively large expansion space of the expansion tower, which is unheated otherwise than by the heat of the products passing into and through it, and the oil is thereby instantly relieved of all pressure, whereupon there is an immediate evaporation of the lighter constituents, the vapor discharging through a vapor pipe 11 leading from the top of the tower, while the heavier products or unvaporized oil falls back into the bottom of the tower, as indicated at 12 and flows by gravity out through a pipe 13. A suitable gage 14 is provided upon the tower for indicating the level of the trapped body of unvaporized oil therein. Connected with the pipe 11, or otherwise communicating with the tower 8, is an automatic safety vent valve 15 and a hand operated vent valve 16. The valve 15 is provided to allow escape of any possible over pressure which may at any time possibly exist in the tower, while the valve 16 is provided to enable any excess pressure to be manually exhausted or the pressure to be manually controlled as occasion may require.

40 The vapor separated from the oil in each tower 8 and discharging through the pipe 11 passes into the base of a dephlegmator or separating chamber 17, comprising a tower or tank having a vapor outlet at its upper end communicating with a vapor discharge pipe 18. In this dephlegmator is

responds in practice with the aggregate area of the pipes 23, thus allowing easy flow of the vapors and preventing any pressure at this point in the system.

The vapor passing through the dephlegmator of unit A is cooled and condensed in the associated condenser, while the vapor discharging from the dephlegmator of unit B is similarly condensed in its associated condenser, and the products in the form of gasoline pass outward from said condensers through pipes 25 and 26 to a receiving house 27, in which they may be inspected and thence to a receiving or storage tank 28, in which the two columns of gasoline of different specific gravities are commingled and from which they may be discharged through a pipe 29 through the action of a pump 30 to any suitable point for storage or use. It will be understood that as the oil from the still 1 of unit A is heated at a very low temperature, the hot vapors may freely rise therefrom in the associated expansion tower 8 without contact with any baffles or other surfaces liable to contaminate or discolor the vapors before they go to the condenser coil, the vapors being cooled sufficiently before entering the dephlegmator to prevent discoloration or other contamination. The distilling unit A will operate to relieve the crude hydrocarbon of a certain proportion of its gasoline content, and the unit B is provided in order that the remainder of the gasoline content may be similarly extracted at a low temperature, without any cracking action, and without any discoloration or contamination of the product. To this end the outlet pipe 13 from the initial expansion tower 8 is connected with a pipe 5', having arranged therein a pump 31, whereby the portion of the oil treated by the first still and discharged through the outlet 13 of the expansion tank of the first unit will be supplied to the still of the second unit and treated on its passage through said unit in the manner previously described for the

grade products combined, and a resultant product obtained which is of mean specific gravity sufficiently high to meet all good grade conditions and at the same time of 5 water white or substantially of water white color, thus avoiding the necessity of subsequent treatment to remove discoloration. By actual test in the operation of a commercial apparatus embodying my invention, 10 I find that I can take off 30% of gasolene from crude oil of 34.6 Baumé gravity, which gasolene is finished stock requiring no acid or caustic soda treatment and no steam stilling whatever, whereby the finished stock 15 may be pumped directly from the apparatus into tank cars without the time, cost and labor required in the treatment of gasolene produced by cracking processes necessary for putting the gasolene into condition for 20 commercial use. Also as the temperatures and pressures employed are not high enough to fractionate any of the distillates, or to fractionate any sulfur content in the crude oil, water white and rigid-test odor-sweet 25 gasolene may be directly produced, without chemical refining, from crude oil containing a high percentage of sulfur.

The unvaporized oil discharged through the pipes 20 from the dephlegmators may, 30 if desired, be conducted to the pipe 5, so as to be pumped with the crude petroleum into the primary still or unit A for retreatment. The residuum deposited in the bottom of the expansion tower 8 of unit B discharges by 35 gravity through a pipe 32 into a cooler, where it is suitably cooled prior to its final discharge. This cooler may comprise a coil 33 submerged in a body of cooling water in the tank 34, and said coil 33 may be connect- 40 ed with a pipe 35 containing a pump 36 for forcing the residuum into a receiving tank 37. This residuum is available for use as fuel or for other purposes and may be dis- 45 charged from the tank 37 by means of a pump 38 through a pipe 39 to any point for further storage or use.

Having thus fully described my invention, I claim:—

1. In an oil distilling apparatus, the combination of a pair of stills, a crude oil supply pipe connected with the inlet of one still,

a pair of expansion tanks, one for each still, pipes leading from the outlets of the respective stills to the respective expansion tanks, a pipe for conducting the unvolatilized oil 55 from the expansion tank associated with the first-named still to the inlet of the second still, vapor outlet pipes leading from the expansion tanks, condensers connected with said vapor outlet pipes, dephlegmators located in said pipes between the expansion tanks and the condensers, and means for conveying the oil separated from the vapors in the dephlegmators and conveying the same to the inlet of the first still for re- 60 65 treatment.

2. In an oil distilling apparatus, the combination of a pair of separate and independent primary and secondary stills, said primary still operating to heat the crude oil to 70 a temperature below cracking temperature, and said secondary still operating to heat the unvolatilized oil from the primary still at a temperature also below cracking temperature but at a temperature above that at 75 which the oil is heated by the primary still, an expansion tower for receiving the heated oil from each still and separating the vapor therefrom, each expansion tower being sep- 80 arate from its still and having a hot oil inlet 85 extending into the bottom thereof and terminat- ing below its horizontal center, said tower being provided with an expansion chamber normally of atmospheric pressure and temperature, a pump for forcing the oil through each still and into the associated ex- 90 pansion tower at a low forcing pressure, the inlet of the tower being located at such a level that the head upon the column of oil flowing thereto will be substantially equal to the forcing pressure, condensers for receiving and condensing the vapors from the expansion chambers, a conductor for con- 95veying the unvolatilized oil from the first expansion chamber to the inlet of the second- ary still, and a dephlegmator arranged di- rectly in the line of flow of the vapor be- 100tween each expansion tower and the associated condenser.

In testimony whereof I affix my signature.

THOMAS J. RYAN.
